(74) Attorney, Agent, or Firm — Christopher P. Maiorana, P.C.

(57) **CLAIM**

The ornamental design for a fence gate bracket, as shown and described.

DESCRIPTION

FIG. 1 is a front perspective view of a fence gate bracket; FIG. 2 is a back perspective view of the fence gate bracket; FIG. 3 is a back-side view of the fence gate bracket; FIG. 4 is a left-side view of the fence gate bracket; and, FIG. 5 is a front-side view of the fence gate bracket. The broken lines represent an environment of use that forms no part of the claim.
